UNITED STATES PATENT OFFICE.

ARTHUR D. BIGGS, OF SOUTH BEND, INDIANA.

BASKET-COVER FASTENER.

Application filed September 27, 1923. Serial No. 665,055.

To all whom it may concern:

Be it known that I, ARTHUR D. BIGGS, a citizen of the United States, residing at South Bend, in the county of St. Joseph and State of Indiana, have invented certain new and useful Improvements in Basket-Cover Fasteners, of which the following is a specification.

This invention relates to certain new and useful improvements in means for fastening the covers upon baskets, particularly of the wooden stave type.

Wooden stave baskets are widely used as containers for the transportation of various commodities, especially grocery items, and these baskets are usually closed by means of a solid veneer top member or cover, the edge of which lies substantially flush with the outside top hook of the basket, when in place. An objection to the use of these baskets for the above purpose, is that no commercially practical and simple means of an effective nature have been heretofore provided for securing the covers in place, so as to reduce the possibility of pilferage of the contents of the basket to a minimum.

It is accordingly an object of the present invention to provide a cover fastening means for baskets of this character which will supply the above needs and which is so constructed as to meet with all of the requirements for a successful commercial use.

Another object of the invention is to provide a basket cover fastening device which embraces the desired qualities of simplicity and durability of construction as well as efficiency in operation.

A further object of the invention is to provide a fastening device embodying wire members effectively connected at the center of the cover and having their ends attached to the basket in such manner that such ends are concealed when the cover is secured in place for thereby reducing the likelihood of pilferage to a minimum.

Other objects will appear as the nature of the invention is better understood, and the same consists in the novel form, combination and arrangement of parts hereinafter more fully described, shown in the accompanying drawing and claimed.

In the drawing, Figure 1 is a top plan view, partly broken away, of a basket, having the cover thereof fastened by means of a fastening device constructed in accordance with the present invention, and

Figure 2 is a fragmentary sectional view, taken substantially upon the line 2—2 of Figure 1.

Referring more in detail to the drawing, 60 the basket consists of a body portion formed of a plurality of thin wooden staves 5 which are of substantially U-shape and arranged so as to cross each other at the center of the bottom of the body portion, the legs of the 65 staves extending upwardly to provide the circular wall of the body, and the free ends of the staves being fastened between concentric hoops 6 and 7 by tacking or the like, the hoops 6 and 7 being hereinafter 70 respectively referred to as the outer and inner hoops at the top of the basket body. The open top of the basket thus formed is usually closed by means of a solid veneer top or cover disc 8 which is of such diameter as to 75 have the edge thereof flush with the outer surface of the outer hoop 6, the cover having its marginal portion resting upon the upper edges of the staves and hoops as is well known in the art.

In accordance with the present invention, the cover 8 is secured in place by means of a novel form of fastening device including two substantially U-shaped wire members 9 and 10, that are preferably formed with 85 diverging legs, the free end portions of which are extended downwardly along the outer surface of the adjacent portion of the outer hoop 6 as indicated at 11, and are then directed upwardly between the staves 90 and the outer hoop as indicated at 12, the free ends of the legs being then directed inwardly over the upper edges of the staves and the inner hoop 7 and finally directed 95 inwardly as at 12 at the inner surface of the hoop 7 as shown clearly in Figure 2. The central portions of the fastener members 9 and 10 are disposed substantially at the center of the cover 8 as shown in Figure 1, and the central portion of one of these 100 members is twisted about the central portion of the other of said members as indicated at 13 so as to tightly bind the cover in place.

In the use of the device, the free ends of the members 9 and 10 are engaged with the basket as shown in Figure 2, after which the cover 8 is slid into place beneath the major portion of the fastener members as shown in Figure 1. The central portion of the member 10 is then tightly twisted about the central portion of the member 9 so as 110 to draw the legs of said members tight and

to securely fasten the cover in place. It will thus be seen that the ends of the members that are engaged with the basket are concealed by the cover, and as the twisting of the central portion of one fastener member from the central portion of the other would take considerable time, the likelihood of pilfering of the contents of the basket is rendered slight. Also, it is not readily apparent to one unfamiliar with the present device, that the cover might be removed in this manner.

From the above description, it will be seen that I have provided a very simple and durable form of basket cover fastening means which may be cheaply and easily manufactured and installed, and which will effectively serve its intended purpose.

Minor changes may be made without departing from the spirit and scope of the invention as claimed.

What I claim as new is:

1. In combination with a basket having inner and outer hoops at the upper portion thereof and a cover disposed upon the hoops with the edge of the cover flush with the outer surface of the outer hoop, means for fastening the cover in place comprising a pair of substantially complemental U-shaped wire members having their central portions twisted together at the center of the cover and arranged with the legs thereof extending outwardly, the free ends of the legs of said members being interlocked with said hoops beneath the margin of the cover.

2. In combination with a wooden stave basket having the staves thereof secured at their free upper ends between inner and outer concentric hoops, of means for securing a cover upon the top of said basket comprising a pair of complemental substantially U-shaped wire members, the free ends of

said wire members being extended downwardly along the outer surface of the outer hoop and then upwardly between the hoops and finally over the upper edge of the inner hoop and down against the inner surface of the inner hoop.

3. In combination with a wooden stave basket having the staves thereof secured at their free upper ends between inner and outer concentric hoops, of means for securing a cover upon the top of said basket comprising a pair of complemental substantially U-shaped wire members, the free ends of said wire members being extended downwardly along the outer surface of the outer hoop and then upwardly between the hoops and finally over the upper edge of the inner hoop and down against the inner surface of the inner hoop, the central or intermediate portion of one of said fastener members being twisted about the central portion of the other of said members above the center of the cover when the latter is in place.

4. A fastening means for covers of stave baskets comprising a pair of complemental substantially U-shaped wire members adapted to have their intermediate portions twisted together above the center of the cover and adapted to have the free ends of the leg portions thereof interlocked with the top of the basket beneath the cover, said basket having the staves connected at the top of the basket by inner and outer concentric hoops, the interlocking connection between the ends of the wire members and the top of said basket comprising passing said ends about the outer hoop with a portion of the ends passing between the hoops and then downwardly against the inner side of the inner hoop.

In testimony whereof I affix my signature.
ARTHUR D. BIGGS.
